OR THE LIKE

Howard H. Kulow, Berea, Ohio, assignor to Wilson
Plastics, Inc., Sandusky, Ohio, a corporation of Ohio

Filed Jan. 31, 1962, Ser. No. 68,587

Term of patent 14 years

(Cl. D58—17)

Fig. 1

Fig. 3.

Fig. 2

FIG. 1 is a perspective view showing one side of the container for dairy products or the like embodying the design of the present invention as viewed from above;

FIG. 2 is a perspective view of the container for dairy products or the like showing the side opposite to that of FIG. 1 as viewed from below.

FIG. 3 is an enlarged fragmentary sectional view thereof taken on line 3—3 of FIG. 1.

The characteristic feature of my design resides in the combination on the container disclosed of the plain upper portion meeting the vertically ribbed lower portion in the sinuous wave about the periphery, all as shown.

I claim:

The ornamental design for a container for dairy products or the like, substantially as shown and described.
